UNITED STATES PATENT OFFICE.

CHARLES SPENCER TATE, OF CHICAGO, ILLINOIS, ASSIGNEE OF ONE-HALF TO FRANK M. OSTERBERG, OF ROCKFORD, ILLINOIS.

RAZOR-GUARD.

1,034,743.

Specification of Letters Patent. Patented Aug. 6, 1912.

Application filed February 1, 1911. Serial No. 606,031.

To all whom it may concern:

Be it known that I, CHARLES SPENCER TATE, a citizen of the United States, residing at Chicago, county of Cook, State of Illinois, have invented a certain new and useful Improvement in Razor-Guards, and declare the following to be a full, clear, and exact description of the same, such as will enable others skilled in the art to which it pertains to make and use the same, reference being had to the accompanying drawings, which form a part of this specification.

My invention relates in general to guards for razors and in particular to detachable guards which may be applied to razors of various sizes.

Many who are accustomed to razors of the ordinary type find it inconvenient to use the various so-called "safety razors". These latter razors have the advantage over the ordinary razor of affording more or less protection against injury through cutting.

The primary object of my invention is to provide a safety guard which will not only prevent deep cuts, but which will smooth the skin in advance of the cutting edge, keeping the skin smooth and flat, and preventing it from being injured as is the case where the skin can roll up under the guard.

A further object of my invention is to provide a safety guard which may easily be adjusted to fit razors of different sizes.

A still further object of my invention is to provide a safety guard for razors which will be simple in construction, inexpensive in manufacture, and efficient in use.

The various features of novelty whereby my invention is characterized will hereinafter be pointed out with particularity in the claims; but, for a full understanding of my invention and of its objects and advantages, reference may be had to the following detailed description taken in connection with the accompanying drawing, wherein:

Figure 1 is a side elevation of my improved guard in position on a razor blade; Fig. 2 is a view looking in the opposite direction from Fig. 1, the razor being shown in dotted lines; Figs. 3 and 4 are sections

on lines 3-3 and 4-4 of Fig. 1, respectively; and Fig. 5 is an enlarged view of a fragment of the guard, illustrating the 55 graduations on the fingers.

In its simplest form, my guard comprises a sheet of spring metal folded upon itself so as to produce a trough-like structure whose sides are of unequal widths, the 60 width of the trough increasing from the mouth toward the closed end. The wide side of the trough has a series of guard fingers along its free edge. The narrow wall of the guard engages with the side of the 65 razor blade and serves as a spring to press it against the opposite side. Suitable means are provided for adjusting the blade in and out and for locking it in position. I prefer so to shape the guard that the blade has 70 what may be termed a three-point or a three-line bearing, the bearing on one side being upon the free edge of the narrow side of the trough and the two bearings on the other side being near the cutting edge of the 75 blade, and near the back. The last-mentioned bearing is preferably afforded by a locking screw. The guard fingers may be graduated so as to guide the user in adjusting the blade in and out, making it easier 80 for him to set the blade for a close shave or a medium shave.

Referring to the drawing, 1 represents a strip of spring sheet metal having a series of small fingers, 2, at one of its long edges. 85 The strip is bent along a longitudinal line parallel with the latter edge so as to form a long trough-like member which decreases gradually in width as the mouth is reached. In the arrangement shown, the portion of 90 the strip which is bent over is in the form of ears, 3, the ears being long enough to engage at their free ends with the side of the razor blade at about the longitudinal medial line. The fingers are curved, being inclined outwardly at their bases and then turning inwardly again toward their free ends. By this arrangement the portion of the strip along the base of the fingers serves as a rib which will engage with the side of a 100 razor blade near the cutting edge and hold the cutting edge clear of the fingers.

Within the trough-like holder lies a long strip, 4, which is carried upon the inner ends

2
of thumb screws, 5, passing through the bottom portion of the trough. The member 4 is adapted to engage with the back of a razor so as to determine the position of the cutting edge lengthwise of the teeth. The member 4 may conveniently be secured to the inner ends of the screws by riveting them and therefore, I place the screws opposite to the spaces between the ears, 3, so that the riveting may take place after the holder 10 has been bent into shape.

For locking a blade in its adjusted positions, I provide a thumb screw, 6, which passes through the wide side of the trough so as to engage with the side of the razor 15 near the back thereof.

Fig. 3 most clearly illustrates the manner of adjusting a blade and the peculiar conditions which exist during the adjustment and 20 use of the blade. In this figure, 7 represents the blade and it will be seen that it is narrower at the back than the width of the trough at this point. At one side it bears 25 against the locking screw, 6, near the back and against the bearing rib or shoulder, 8, adjacent to the cutting edge. On the opposite side the free ends of the ears, 3, engage therewith at a point between the locking screw and the bearing rib or shoulder, 8. It will thus be seen that when the locking 30 screw is tightened, placing the spring ears under tension, there is no tendency to swing the cutting edge away from the guard fingers as would be the case if the locking 35 screw were lower than the bearing point between the blade and the spring fingers. Consequently, if the locking screw is tightened a little too much, it can have no bad effect on the action of the razor in shaving. 40 By shaping the guard fingers so that they approach the plane of the cutting edge near their outer ends, they will press upon the skin in advance of the cutting edge and tend to push it forward as the shaving operation 45 progresses keeping it taut directly in front of the cutting edge so that the formation of wrinkles and consequent cutting of the face is prevented.

To facilitate the in and out adjustment of 50 the blade I place suitable graduations on the guard fingers, the closeness to which the razor will cut depending upon the positions of the cutting edge measured lengthwise of the guard fingers. In the arrangement 55 shown, I have provided each finger with two separated marks, 9 and 10. When the blade is set so as to place its edge along the line of marks, No. 9, the razor will shave more closely than when set farther back; consequently, the user will soon learn where to 60 set the blade in order to give the desired closeness in shaving and need not experiment whenever he takes off the guard and puts it on again, in order to get the blade 65 positioned properly.

While I have illustrated and described in detail only a single preferred form of my invention, I do not desire to be limited to the particular structural details so illustrated and described; but intend to cover all forms 70 and arrangements which fall within the terms employed in the definitions of my invention constituting the appended claims.

I claim:

1. In combination, a trough-like member 75 having sides of unequal widths, guard fingers along the free edge of the wide side of the trough, an adjusting screw carried by the wide side of the trough at a considerable distance from said fingers, a razor blade 80 lying in the trough and engaging with said screw and with the wide side of the trough near the bases of said fingers, the narrow side of the trough being resilient and engaging with the blade at a point between 85 the points of engagement of the blade with the wide side of the trough and with the adjusting screw, the width of the bottom of the trough being greater than the thickness of the back edge of the blade so as to leave 90 the blade out of engagement with the narrow side of the trough except adjacent to the free edge of the latter.

2. In combination, a trough-like member 95 having sides of unequal widths, guard fingers along the free edge of the wide side of the trough, an adjusting screw carried by the wide side of the trough at a considerable distance from said fingers, a razor blade lying in the trough and engaging with said 100 screw and with the wide side of the trough near the bases of said fingers, the narrow side of the trough being resilient and engaging with the blade at a point between the points of engagement of the blade with the wide side of the trough and with the adjusting screw, and an adjusting screw carried by the bottom of the trough and engaging with the back of the blade, the width of the bottom of the trough being greater than the thickness of the back edge of the blade so as to leave the blade out of engagement with the narrow side of the trough except adjacent to the free edge of the latter.

3. In combination, a trough-like member 1 having sides of unequal widths, guard fingers along the free edge of the wide side of the trough, an adjusting screw carried by the wide side of the trough at a considerable distance from said fingers, a razor blade 1 lying in the trough and engaging with said screw and with the wide side of the trough near the bases of said fingers, the narrow side of the trough being resilient and engaging with the blade at a point between the points of engagement of the blade with the wide side of the trough and with the adjusting screw, said fingers being curved so as to extend away from the plane of the razor blade and then inwardly so as to bring

their extreme outer ends nearest the plane of the blade, the width of the bottom of the trough being greater than the thickness of the back edge of the blade so as to leave the 5 blade out of engagement with the narrow side of the trough except adjacent to the free edge of the latter.

In testimony whereof, I sign this specification in the presence of two witnesses.

CHARLES SPENCER TATE.
